WARREN F. CLARK, OF PHILADELPHIA, PENNSYLVANIA

DESIGN FOR A COMBINED URN AND MEMORIAL TABLET

Application filed October 1, 1930. Serial No. 37,100. Term of patent 7 years.

To all whom it may concern:

Be it known that I, WARREN F. CLARK, a citizen of the United States of America, residing at Philadelphia, in the county of Philadelphia and State of Pennsylvania, have invented a new, original, and ornamental Design for a Combined Urn and Memorial Tablet, of which the following is a specification, reference being had to the accompanying drawings, forming a part thereof.

I claim:

The ornamental design for a combined urn and memorial tablet as shown.

WARREN F. CLARK.
